UNITED STATES PATENT OFFICE

CARVER C. BROWN, OF EL PASO, TEXAS.

RAILWAY-CONSTRUCTION CAR.

SPECIFICATION forming part of Letters Patent No. 487,045, dated November 29, 1892.

Application filed August 3, 1892. Serial No. 442,042. (No model.)

To all whom it may concern:

Be it known that I, CARVER C. BROWN, a citizen of the United States, residing at El Paso, in the county of El Paso and State of Texas, have invented certain new and useful Improvements in Railway-Construction Cars, of which the following is a specification.

This invention relates to an improvement in dumping-cars for use in the construction of railway road-beds; and the object is to provide for operating the car by means of compressed air or steam from the locomotive.

The accompanying drawings illustrate a construction for carrying out my invention.

Figure 1 shows a side elevation of a car embodying my invention; Fig. 2, an end view of the same; Fig. 3, a top view of the car open, as in the act of dumping its load; Fig. 4, a cross-section on line 4 4 of Fig. 1; Fig. 5, a longitudinal section of the car in closed condition; Fig. 6, a cross-section on line 6 6 of Fig. 3, with the car open, as in the act of dumping its load; Fig. 7, a bottom view of the car; Fig. 8, a detail view illustrating the style of release or exhaust valve employed, the casting of the same and the pipes leading thereto being in section. Fig. 9 shows a detail sectional view of a valve-box and valves therein for controlling the flow of fluid.

The frame of the car comprises end pieces or bolsters, with sills 2 bolted thereto and longitudinal beams or sleepers 3 and brace-roads 4 connecting said bolsters. The latter may each be in one piece, or may each consist of two pieces 5 6, as here shown, with an interposed metal plate 7. In the present instance there are four longitudinal beams or sleepers 3, the two inside ones being higher than the two outside ones, and all having inclined upper surfaces 8. Inclined cross-pieces 9 connect the said beams at intervals and are faced with metal on the upper side to form slideways, a number of the said facings 10 extending all the way across the car-frame, with an apex at the middle.

The car-platform comprises two longitudinal sections, each of which consists of suitable flooring 11, fastened on slide-blocks 12, which have inclined lower sides, metal-faced to slide on the inclined slideways 10. The said slide-blocks 12 have inclined slots 13, which are

engaged by a pivot-rod 14, extending longitudinally of the car and fastened in the end bolsters 5 6.

The closed condition of the car is with the platform horizontal and the inner edges of the two sections fitting together and the rods 14 occupying the outer end of the slots 13. The said platform-sections slide down and away from each other on the ways 10 and tilt to an approximately -vertical position, turning on the rods 14, to dump the matter which they carry. The interposed plate 7 and facings 16 on the bolsters prevent the pivot-rods wearing into the wood of the bolsters. Blocks 44 at the middle of the truck form guides, on either side of which the middle slide-blocks fit. The platform - sections have upright guard-boards 15 at their inner confronting edges to prevent dirt from falling between them and into the operating mechanism below. When the platform-sections are closed together, they are prevented from jolting up and down by the engagement of pins 17, which project from the slide-blocks 12 under catches 18, fastened on the upper sides of the middle sleeper-beams 3.

I employ the following mechanism to hold the platform-sections closed and prevent them from sliding outward and down on the ways 10. A pair of double sliding latches are provided, and each consists of two slide-bars 19, fitting against the inner sides of the middle sleeper-beams of the car-frame and guided by pins 20, which engage slots 21 in said slide bars. Each of the latter projects at one part above the said beams and has an inclined flange 22, extending over the top surface of the beam, and a notch or detent 23, adjoining said projecting part. The slide-bars are connected together by a cross-bar 24.

Each platform-section has a pair of spring-arms 25 on the under side whose inner ends are bent rounded and carry antifriction-rollers 26, to take over the projecting parts of the slide-bars 19 of the latches, the said rounded ends riding upon the inclined flanges 22. The latches may be moved to bring the rollers on the spring-arms at the notches or detents 23, when the platform-sections may slide out and down, said rollers passing through the said notches. Each of the sliding latches has a

rod 27 connected with its cross-bar 24 and jointed to a rocking arm 28, which is mounted on a rock-shaft 29 in bearings on the under side of the center beams of the car. In the 5 present instance said rocking arm is in the form of a loop which extends below said rock-shaft.

A pair of drums 30, forming in effect one double drum, is mounted at each end of the 10 car between the center beams thereof, and each drum of a pair is joined to one of the platform-sections by a flexible connection 31, which passes over a roller 32, mounted above the drum in a suitable bracket 33, and set obliquely. Said flexible connection passes 15 through a guide 34 on the inner part of the platform-section, and is joined to a strip 35, secured across the outer side of said platform-section. (See dotted lines in Fig. 6.) Two 20 drums on one side of the central longitudinal line of the car are connected with one of the platform-sections and the other two with the other section. It will be seen the winding of the flexible connections upon the drums will 25 draw the platform-sections down on the slide-ways 10 and then inward until they meet. A cog-wheel 36 is interposed between each pair of drums, and a toothed segment 37 gears into said cog-wheel and has a depending bifurcated arm 38, said segment being mounted 30 on a shaft in bearings on the under side of the center beams of the car.

A cylinder 39 is supported by brackets 40, depending from the central beams of the car, 35 and two pistons 41 are in said cylinder. Each of said pistons has a rod 42, which extends through the bifurcated arm 38 of one of the segments 37 and also through the looper of one of the rocking arms 28, and said rod has projections 43 on opposite sides of each of said parts—viz., the bifurcated arm and the looped rocking arm. A pipe 45 extends from a box 46, secured on the under side of one of the car-frame sills 2, and has branches 47, 47^a, which 40 enter the two opposite ends of the cylinder 39. Another pipe 48 extends from said box 46, and has a branch 49, which enters the middle of the cylinder. An exhaust-valve is inserted in each pipe, and comprises a casing 50, into which 45 the pipe opens, and a piston slide-valve 51, fitting closely the bore of said casing and having an annular passage 52 on the exterior and a central passage 53 extending through it in the line of the pipe, but being of smaller area 50 than the bore of said pipe. This through-passage is indicated in dotted lines in Fig. 8. The valve has a guide-stem 54, fitting a bore of the casing, and a spring 55 fits about said stem and holds the valve to the right. A branch 60 56 of the pipe 48 enters the casing of the exhaust-valve in the pipe 45, and is normally closed by the piston-valve having position over it, and a branch 57 of the pipe 45 enters the casing of the exhaust-valve in the other 65 pipe 48, and is likewise normally closed by the piston-valve in said casing. In each valve-

case an exhaust-port 58 is in the side opposite the branch pipe, and is adapted to be placed in communication therewith through the annular passage 52, when the piston-valve is 70 moved to the left. A train-pipe 59, for carrying the fluid from the locomotive, enters the box 46. Each of the pipes 59, 45, and 48 is controlled by a separate valve in the form of an ordinary one-way cock 60, fitting a bore in 75 the box 46, and by means of said valves either of the pipes 45 or 48 may be put in communication with the train-pipe. Said box communicates with the train-pipe on the next car by a nipple 61. Each valve 60 has a stem 62, extending upward along the bolster 5 of the car-frame in suitable keepers and provided with a handle 63 for turning it.

The operation is as follows: In the normal closed condition of the car the pistons 41 are 80 at the two opposite ends of the cylinder and the flexible connections 31 are wound upon the drums. Compressed air is between the pistons, having been admitted through the pipe 48 by opening the valve 60, which controls said pipe. 85 To release the platform-sections and dump the load carried thereon, the said valve is closed and the valve controlling the pipe 45 is opened. The compressed air now enters said pipes 45, and reaching the exhaust-valve in the 90 same exerts pressure against the head of the piston-valve 51 and forces the same back to a position where the annular passage 52 establishes a communication between the branch pipe 58 and the port 58 and thereby 95 releases the compressed air from between the pistons 41. At the same time compressed air passes through the branch pipe 47 into one end of the cylinder and through the central passage 53 in the exhaust-valve to the branch 100 pipe 47^a and therethrough into the opposite end of the cylinder. Compressed air being thus introduced on the outer sides of the two pistons and that between being exhausted, the pistons are forced together. This causes the 105 projections on the piston-rods to turn the segments 37 and unwind the drums 30 and also to shift the rocking arms 28 and thereby slide the double latches to a position where the ends of the spring-arms 25 may pass 110 through the notches 23 in the said sliding latches. The platform-sections will now slide down the inclined ways and dump the load. To reclose the platforms, the controlling-valve of the pipe 45 is closed and that of the pipe 115 48 opened and the reverse action takes place, the exhaust-valve in the pipe 48 being opened by the air-pressure to release the compressed air on the outer sides of the pistons and compressed air entering between the pistons to 120 force them apart and thereby wind up the flexible connections on the drums and draw the platform-sections to the closed position. At the same time the rocking arms 28 are shifted and the sliding latches 19 moved back 125 to a position where the spring-arms 25 will take over them. After one car is dumped the 130

air is carried to the next car through the train-pipe 59 by opening the valve 60, controlling the latter and closing both the other controlling-valves. The said valves 60 are operated by turning the stems 92.

It will be seen that with this construction each car of a train may be operated independently of the others and a very powerful fluid agent is employed to operate the dumping apparatus.

It is evident my invention may be embodied in many forms differing from that here shown in arrangement and construction of parts.

Having thus described my invention, what I claim as new, and desire to secure by Letters Patent, is—

1. In a railway-construction car, the combination of a dumping-platform, a drum, a flexible connection between said drum and platform, and means for revolving said drum by fluid-pressure, substantially in the manner and for the purpose described.

2. In a railway-construction car, the combination of a dumping-platform, a drum, a flexible connection between said drum and platform, a cylinder for fluid, a piston in said cylinder and having a rod, and suitable connections between the said rod and the drum, whereby the latter may be revolved by application of fluid-pressure to the piston.

3. In a railway-construction car, the combination of a dumping-platform, a drum, a flexible connection between said drum and platform, a cylinder for fluid, a piston in said cylinder and having a rod, and a segment for actuating said drum and connected with the piston-rod, whereby the drum may be revolved by application of fluid-pressure on the piston.

4. In a railway-construction car, the combination of a dumping-platform, a pair of drums, flexible connections between said drums and the said platform, a cylinder for fluid, two pistons in said cylinder, each having a rod, and suitable connections between said rods and the two drums, whereby fluid-pressure acting to move said pistons toward or away from each other operates the platform.

5. In a railway-construction car, the combination of a sliding platform, a cylinder for fluid, a piston in said cylinder and having a rod, suitable connections between said rod and the sliding platform, whereby the latter is operated by fluid-pressure on the piston, a latch to hold the said platform, and suitable connections between said latch and the piston-rod, whereby the platform may be released by the movement of the latter.

6. In a railway-construction car, the combination of a sliding platform, a cylinder for fluid, a piston in said cylinder and having a rod, suitable connections between said rod and the sliding platform, whereby the latter is operated by fluid-pressure on the piston, a sliding latch engaging a projection on the platform, and suitable connections between

said latch and the piston-rod, whereby the movement of the latter may throw the latch out of engagement with the projection on the platform.

7. In a railway-construction car, the combination of a sliding platform, a cylinder for fluid, a piston in said cylinder and having a rod, suitable connections between said rod and the sliding platform, whereby the latter is operated by fluid-pressure on the piston, a sliding latch having a projecting inclined part, a spring-arm on the sliding platform having an end to take over the projecting inclined part of said latch, and suitable connections between said latch and the piston-rod, whereby the movement of the latter may throw the latch out of engagement with the projection on the platform.

8. In a railway-construction car, the combination of a sliding platform, a cylinder for fluid, a piston in said cylinder and having a rod, a suitable connection between said rod and the sliding platform, whereby the latter is operated by fluid pressure on the piston, a sliding latch engaging a projection on the platform, and a rocking arm connecting the latch and piston-rod, whereby the movement of the latter may throw the latch out of engagement with the projection on the platform.

9. In a railway-construction car, the combination of a platform made in two sliding and tilting sections, a drum, flexible connections between said drum and the two sections of the platform, a cylinder for fluid, a piston therein having a rod, and suitable connections between said rod and the drum, whereby the latter may be revolved by application of fluid pressure on the piston.

10. In a railway-construction car, the combination of a platform made in two sliding and tilting sections, a cylinder, piston, and piston-rod, suitable connections between the said rod and the sections of the platform, whereby the latter may be operated by application of fluid pressure on the piston, a double sliding latch engaging projections on the two sections of the platform, and connections between the said latch and the piston-rod, whereby it may be moved out of engagement with the platform-sections by said piston-rod.

11. In a railway-construction car, the combination of the car-frame having inclined slideways, two platform-sections having slotted slide-blocks fitting on said slideways, pivot-rods engaging the slots in the said slide-blocks, and suitable means for sliding and tilting said platform-sections.

12. In a construction car, the combination of a cylinder for fluid, two pistons therein, piston-rods, suitable connections between the latter and the dumping apparatus, whereby the same is operated by movements of the pistons toward and away from each other, a pipe for conducting fluid into the cylinder on the outer sides of the pistons, a pipe for conducting fluid between the two pistons, valves

for controlling the flow of fluid through said pipes, and an automatic exhaust-valve in each of the said pipes and having communication with the other pipe, whereby to exhaust the fluid from the cylinder in the manner described.

13. In a construction car, the combination of a cylinder for fluid, two pistons therein, piston-rods, suitable connections between the latter and the dumping apparatus, whereby the same is operated by movements of the pistons toward and away from each other, a pipe for conducting fluid into the cylinder on the outer sides of the pistons, a pipe for conducting fluid between the two pistons, valves for controlling the flow of fluid through said

pipes, and an automatic exhaust-valve in each of the said pipes and having communication with the other pipe, whereby to exhaust the fluid from the cylinder, each of said exhaust-valves comprising a suitable casing into which the pipes lead, and having an exhaust-port, a piston-valve in said casing and having an exterior annular passage and a central through-passage, and a spring acting on said valve.

In testimony whereof I affix my signature in the presence of two witnesses.
